UNITED STATES PATENT OFFICE.

CARL H. FOWLER, OF NEW YORK, N. Y.

APPARATUS FOR SHALLOW-WATER BOATS.

1,163,077.

Specification of Letters Patent.

Patented Dec. 7, 1915.

Application filed June 30, 1914. Serial No. 848,129.

To all whom it may concern:

Be it known that I, CARL H. FOWLER, a citizen of the United States, residing in the city, county, and State of New York, have 5 invented a certain new and useful Apparatus for Shallow-Water Boats, of which the following is a specification.

My invention relates to an apparatus which can be installed in boats intended to 10 navigate through shallow water.

The object of the invention is to construct a simple apparatus which can be bolted or fastened to the bottom of any shallow water boat, even those floating in a few inches of 15 water, and then a screw operated therein efficiently as a power boat without slipping or racing of the propeller.

In order that my invention may be clearly understood reference is hereby made to the 20 accompanying drawings forming a part of this application and illustrating certain forms of construction by which my invention may be carried out.

In the drawing, Figure 1 represents a vertical longitudinal section through the apparatus which may be described as a "removable tunnel", with vacuum chamber attached, propeller, engine and vacuum pump complete for installation in any flat bottomed 25 boat. Fig. 2 represents a top plan view of the same. Fig. 3 represents a transverse section on the line 3—3 of Fig. 1, and Fig. 4 represents a transverse vertical cross-section on the line 4—4 of Fig. 1, partly shown in 30 perspective.

Referring to the drawings, the apparatus which as stated may be applied as an attachment to an existing boat intended to navigate through shallow water comprises a 35 frame 1 preferably made of steel or other suitable metal. This frame is shaped to form a propeller chamber or tunnel within the bottom of the boat, frame 1 being provided with a horizontally extending flange 2 around the same provided with holes extending through the flanges through which bolts 3 may be passed to secure the frame to the bottom of the boat, it being understood that when the device is mounted in position in a 40 boat, a suitable section of the bottom of the boat is cut away, the horizontal flange 2 of the frame being bolted or otherwise secured to the portion of the bottom of the boat surrounding the cutaway part so that the frame 45 1 will form a propeller chamber extending upwardly within the body of the boat and

open at the bottom. The opening in the bottom of the boat about which frame 1 is positioned is preferably rectangular in shape, although this opening in the boat and the frame positioned about the same may be of a different shape if desired. The joint made between the frame 1 and the bottom of the boat is calked or otherwise made tight to prevent the entrance of water into 50 the interior of the boat. The propeller chamber thus formed is provided with an upwardly and rearwardly sloping forward wall or roof portion 4 and a downwardly and rearwardly sloping rear wall or roof portion 5. A vacuum chamber 6 is mounted upon frame 1 above the highest point of the chamber formed by frame 1 and opens into the chamber as shown. Chamber 6 may be mounted upon frame 1 in any suitable manner, but preferably in the manner shown in the drawings in which the lower end of the horizontal chamber 6 is screw-threaded on its exterior and is screwed into a base portion 7 which is integral with or secured to 55 the top of frame 1 surrounding the opening 8 therein leading into the propeller chamber 9 formed by the frame 1.

The vacuum chamber 6 is provided with an exhaust pipe 10 leading to a vacuum pump 11 by which air may be exhausted from the upper part of the vacuum chamber in order to draw water into the propeller chamber 9 and vacuum chamber 6 in order to permit the propeller within the 60 propeller chamber to operate in a solid body of water. In my preferred construction, pipe 10 extends downwardly from the upper part of chamber 6 within the chamber and is led outwardly through the wall 65 of chamber 6 near the base of the chamber for its connection with the vacuum pump, the pipe extending through a suitable watertight joint in the wall of the chamber. By this arrangement, a compact structure is 70 formed which may be readily packed and shipped. A propeller shaft 12 is provided extending through the forward wall 4 of chamber 9 through a bearing 13 integral with or secured to the frame 1 in such manner as to make a substantially water tight 75 joint. The shaft 12 is adapted to be rotated by an engine 14 of any suitable construction which may be mounted within the boat, and a propeller 15 is mounted within 80 chamber 9 upon the end of shaft 12. Preferably, shaft 12 is so mounted as to be sub-

stantially parallel with the rear wall 5 of the propeller chamber and also preferably rear wall 5 of the propeller chamber slopes at a more gradual angle and is longer than the forward wall portion 4 of the chamber. 5 A manhole 16 may be provided to cover an opening in the upper part of frame 1 which may be opened for the inspection of the propeller when the apparatus has been 10 mounted in place in a boat.

From the above, it will be evident that by my invention a detachable propeller chamber and coacting parts are provided which may be mounted in place upon the 15 bottom of an ordinary boat in which a hole has been cut or a section removed of the side of the inside dimensions of the flanged base of the frame 1 so that an ordinary flat bottom boat or other shallow draft boat may 20 be converted into a power boat operated by a propeller, still able to navigate in very shallow water.

Having now particularly described my invention, what I claim and desire to protect by Letters Patent is as follows:—

1. As an attachment adapted to be mounted in a boat about an opening in the bottom of the boat, a removable tunnel comprising a frame shaped to form an upwardly rising chamber, said frame having a flanged base portion, a vacuum chamber mounted upon said frame, and communicating with the chamber formed by said frame, a vacuum 30

pump mounted on said frame, and an exhaust pipe extending from the upper portion of the interior of said vacuum chamber through the lower portion of the wall of said chamber and connected to said pump, said frame having a bearing on the forward wall thereof through which a propeller shaft may be extended into the interior of said frame, substantially as set forth. 35

2. As an attachment adapted to be mounted in a boat about an opening in the bottom of the boat, a removable tunnel comprising a frame shaped to form an upwardly rising chamber, said frame having a flanged base portion, a vacuum chamber mounted upon said frame and communicating with the chamber formed by said frame, and an exhaust pipe extending from the upper portion of the interior of said vacuum chamber through the lower portion of the wall of said chamber, and adapted to be connected to a vacuum pump, said frame having a bearing on the forward wall thereof through which a propeller shaft may be extended into the interior of said frame, substantially as set forth. 40

This specification signed and witnessed this 27th day of June, 1914.

CARL H. FOWLER.
